[75] Inventor: William C. Mertz, Webster Groves, Mo.

Primary Examiner—Susan J. Lucas

[73] Assignee: UMC Industries, Inc., Stamford, Conn.

[57] CLAIM

[**] Term: 14 Years

The ornamental design for an electro-mechanical pulser, as shown.

[21] Appl. No.: 741,055

DESCRIPTION

FIG. 1 is an elevational view of an electro-mechanical pulser embodying my new design.

FIG. 2 is a side elevational view of the electro-mechanical pulser of FIG. 1.

FIG. 3 is a bottom view of the electro-mechanical pulser of FIG. 1.

FIG. 4 is a rear elevational view of the electro-mechanical pulser of FIG. 1.
